UNITED STATES PATENT OFFICE.

FRANK WINDSOR DENISON, OF MONTREAL, QUEBEC, CANADA, ASSIGNOR OF ONE-FOURTH TO GEORGE WILLIAM COOK AND ONE-FOURTH TO IVAN STUART WOTHERSPOON, BOTH OF MONTREAL, CANADA.

MACHINE FOR CUTTING LENGTHS OF CLOTH, &c.

No. 909,854.

Specification of Letters Patent.

Patented Jan. 12, 1909.

Original application filed June 8, 1908, Serial No. 437,460. Divided and this application filed September 3, 1908.
Serial No. 451,594.

To all whom it may concern:

Be it known that I, FRANK WINDSOR DENISON, a citizen of the United States of America, and resident of 55 Papineau avenue, in 5 the city and district of Montreal, in the Province of Quebec, in the Dominion of Canada, have invented certain new and useful Improvements in a Machine for Cutting Lengths of Cloth or other Material; and I 10 do hereby declare that the following is a full, clear, and exact description of the same.

The invention relates to improvements in 15 a machine for cutting lengths of cloth or other material, as described in the present specification and illustrated in the accompanying drawings that form part of the same.

The invention consists essentially in the 20 novel construction and arrangement of parts whereby the material is carried with the lateral movement of the knives in relation to the frame of the machine and the line of cut not disturbed.

The objects of the invention are to supply 25 a simple means of cutting strips of material particularly for such uses as belting, to save waste of material by obviating any chance of the cut getting out of line, and generally to devise a cheap and efficient machine.

30 The drawing is a perspective detail of the mechanism apart from the frame.

Like numerals of reference indicate corresponding parts in each figure.

The present application is a division of 35 application Serial Number 437,460, filed on the 8th of June, 1908.

Referring to the drawing, 1 is the bale of material carried on the shaft 2, said shaft being suitably supported in a frame.

40 3 is a tension roller journaled in suitable bearings in a suitable frame in advance of the shaft 2.

4 and 5 are rollers journaled in a suitable frame at a higher elevation than the roller 45 3 and on the same level, but spaced apart and parallel.

6 is a rod parallelly arranged in the space between the rollers 4 and 5 and supported thereabove by the brackets 7, said rod having a limited slidable movement in its supports.

50 8 are knives adjustably mounted on the rod 6 and set at any desired position thereon

and also arranged to extend downwardly into the space between the rollers 4 and 5 so 55 that when the cloth material is stretched over said rollers, the knife or knives will penetrate the said cloth or material.

9 is a guide adjustably secured on the rod 6 and having a flat face below said rod 60 adapted to engage the edge of the material passing over said rollers 4 and 5, said guide being arranged and set on said rod 6 by a suitable set screw extending therethrough and abutting said rod. 65

10 is a spiral spring encircling the rod 6 inside the bracket 7 and arranged to keep the guide 9 always in contact with the edge 12 of the material, the collar 11 being fixedly mounted on the said rod 6, against which 70 one end of the spring is placed, the other end abutting the bracket 7. It will be thus seen in any movement of the material passing over the rollers in a lateral direction in relation to the frame of the machine, the guide 75 9 will always follow the edge of the material which it abuts and as the guide 9 and the cutting knife 8 are held rigidly, the same distance one from the other, no variations can occur in the line of cut in the material 80 for it must always be the same width as the length of rod between the knife and the said guide, until said knife is readjusted for a different width.

The means of drawing the cloth over the 85 rollers 4 and 5 is neither described nor is it illustrated in the present papers, for the reason that it may be done in so many ways, that is to say, this mechanism may form part with another machine, or else the rollers 4 and 5 may be driven and be of larger 90 diameter than shown and so carry the goods thereover without any further assistance, and again the material may be drawn over by another roll, which may be the receiving 95 roll, therefore, any suitable means as already stated may be employed for insuring the continuous forward movement of the cloth or other material, further, it may not be absolutely essential to the operation of the invention to have a pair of rolls as arranged, that is, a parallel pair of rolls, for one roll might operate equally well and the cut be made on top of that roll into suitable grooves 100 thereon.

105 Various modifications may consequently

be made, without departing from the spirit of the invention.

What I claim as my invention is:

1. In a machine for cutting lengths of cloth or other material, a roll supporting material in passage, a rod supported longitudinally in relation to said roll and adjacent thereto and lengthwise movable, a knife adjustably secured at said rod and arranged 10 to extend into the material passing over said roll, a guide plate adjustably secured on said rod in fixed positions in relation to said knife, and a spring cushion cushioning said rod between said guide plate and the rod support.
2. In a machine for cutting lengths of cloth or other material, a pair of rolls, suitably spaced and supporting the material in 15

passage, a rod supported between said rolls longitudinally in relation to said roll and adjacent thereto and lengthwise movable, a knife adjustably secured to said rod and arranged to extend into the material passing over said main roll, a guide plate adjustably secured on said rod in fixed positions in 25 relation to said knife, and a spring cushion cushioning said rod between said guide plate and the rod support.

Signed at the city and district of Montreal, in the Province of Quebec, in the Dominion of Canada, this third day of August, 1908.

FRANK WINDSOR DENISON.
